(57) **CLAIM**

The ornamental design for a tamper evident ice cream carton, as shown and described.

DESCRIPTION

FIG. 1 is a front perspective view of a tamper evident ice cream carton showing my new design;

FIG. 2 is a rear perspective view thereof;

FIG. 3 is a top plan view thereof;

FIG. 4 is a rear elevational view thereof;

FIG. 5 is a right side elevational view with the left side being a mirror image thereof; and,

FIG. 6 is a bottom view thereof.

The dashed lines in FIGS. 1 and 2 are perforations used for folding the carton.
